UNITED STATES PATENT OFFICE.

GEORGE W. SAWYER, OF NEW YORK, N. Y., ASSIGNOR TO BERNARD LANDE,
OF SAME PLACE.

ELECTRIC LAMP.

SPECIFICATION forming part of Letters Patent No. 254,055, dated February 21, 1882.

Application filed November 29, 1881. (No model.)

To all whom it may concern:

Be it known that I, GEORGE W. SAWYER, of New York, county and State of New York, have invented certain new and useful Improvements in Electric Lamps, of which the following is a specification.

This invention relates to electric-arc lamps, and has for its object to make a simple and reliable feeding device, not liable to derangement, for raising the upper carbon to form the arc between the points of the carbons, and to allow the same to gradually feed down as the carbons are consumed.

This invention consists of two grooved pulleys fixed in yokes depending in brackets from the lower side of the electro-magnetic device. These grooved pulleys have the upper-carbon rod between them, and are held thereto by means of springs so adjusted as regards strength that the carbon rod will fall down freely by its own weight, turning the pulleys as it so descends, but is held between the pulleys when they are prevented from turning. Two brake-arms projecting downward from the moving core or armature of the electro-magnetic device partly surround the grooved pulleys. These brake-arms are brought in contact with the pulleys when the moving core or armature first commences to rise, and so lock them by friction, and then the pulleys, with the carbon rod, move up with the moving core or armature to form the arc between the carbon rods. As the carbons consume, the magnetic action of the current passing through the electro-magnet weakens, the armature with the brake-arms falls and releases the pulleys, and so allows them to turn and the upper carbon to approach the lower one. Said falling of the upper carbon is instantly arrested by the brake-arms when the arc is of normal length. By this arrangement it will be seen that the upper-carbon rod falls with a perfectly steady uniform motion, and is in no wise bruised or marred by the grooved pulley, so the liability of the clamping device becoming inoperative is reduced to a minimum.

The invention also consists in certain improvements in the electro-magnet, which will be fully understood from the following description of the accompanying drawings, to which

I will now refer to more fully describe my invention.

Figure 1 is a vertical section of an electric lamp embracing my improvements, showing the arc formed between the carbon rods. Fig. 2 is a full front view of the clamping and feeding device and its actuating electro-magnets, showing the feeding device free. Fig. 3 is a vertical section of the same cut through the line *x x*, and Fig. 4 is a horizontal section cut through the line *y y*.

The electro-magnet consists of the two helices *a a'*, the upper ends of which are secured to the bar *b* of the frame, made of insulating material, or to the iron plate *c*, which is secured to the bar *b*, and which has two short cores, *c' c'*, fitting for a short distance down into the helices *a a'*. Two other cores, *d d*, fit loosely in the helices *a a'*, and are connected together by the bar *d'*, fitted to slide freely on brackets *e e*, connected to the lower heads of the helices *a a'*. The upper-carbon rod *f* passes through holes in the bar *b*, plate *c*, and bar *d'*. The electric current enters the lamp by the binding-post *g*, passes through the two helices *a* and *a'*, down by the flexible wire *g'*, to the lower end of the carbon rod *f*, and down the carbon *h*, carried thereby, and the lower carbon, *h'*, carried by the bar *h'*, of insulating material, up the side bar, *i*, of the frame, and out of the lamp by the binding-post *j*. The electric current passing through the helices *a* and *a'* causes the cores *d d* to approach the fixed short cores *c' c'*, so that this electro-magnetic device is a combination of a horseshoe electro-magnet and axial magnet, and by this arrangement I have the long movement of axial cores with the advantage of the more powerful attraction of magnets of the horseshoe form.

Passing through holes in the brackets *e e* are the necks of the yokes *k*, the upper ends of which are provided with light springs *k' k'*, to insure the yokes falling down, their limit of downward movement being governed by the ends of slots in their sides coming in contact with the small screws *e' e'* in the brackets *e e*. In the bifurcated ends of these yokes *k k* are pivoted the pulleys *l l*, ground to fit the carbon

rod f , and these pulleys $l l$ are pressed against the rod f by means of the springs $m m$, tending to draw them together, the yokes $k k$ being loosely fitted in the brackets $e e$, to allow of a slight movement of the yokes and pulleys $l l$.

Connected to the bar d' , joining the cores $d d$, are the two brake-arms $n n$, extending downward and partly surrounding the pulleys $l l$. These brake-arms are away from the pulleys when the cores $d d$ are in their lowest position, so that the pulleys are free to be rotated by the falling of the carbon rod f , the tension of the springs $m m$ being such as to cause the pulleys $l l$ to rotate when the carbon rod f moves longitudinally, and to hold the rod between them by friction when their rotation is prevented, which occurs as soon as the brake-arms $n n$ come in contact with them upon the cores $d d$ being attracted within the helices a and a' . The pulleys $l l$ and the rod f are then raised up the extent of such upward movement, which forms the arc, this movement being governed by the set-screws $o o$, passing through the bar d' and butting against the heads of the helices $a a'$. Instead of only two pulleys $l l$ and their supporting-yokes and brakes, three or more may be arranged around the rod f , such a modification being easily arranged by any skilled mechanic; so a further description here of the same is unnecessary.

It is obvious that other forms of actuating electro-magnets may be used in combination with this improved carbon-rod clamping and feeding device. For instance, the plate c , with short cores $c' c'$, may be removed, leaving the magnet, as shown, an axial magnet of horseshoe form; or a single straight hollow-core axial magnet or an ordinary horseshoe-magnet with moving armatures may be used.

It is also evident that any of the forms of electro-magnets having two or more coils of

wire connected upon the differential principle may be used; so I do not wish to confine myself to the combination of the particular form of electro-magnet here shown with the carbon-rod 45 clamping and feeding device; but

What I claim, and desire to secure by Letters Patent, is—

1. An electric-arc-lamp regulator composed of the following instrumentalities in combination: friction guide-pulleys embracing the upper-carbon-holding rod, and the moving core or armature of an electro-magnetic device provided with brake-arms adapted to prevent the rotation of the guide-pulleys and raise 55 them with the carbon-holding rod clamped between them, when the core or armature is acted on by induction from the electric current passing through the coils of the electro-magnetic device, substantially as set forth. 60

2. In combination with the moving core or armature of an electro-magnet, the brake-arms $n n$, pulleys $l l$, fitted in vertically-sliding bearings, and the carbon rod f , substantially as and for the purpose hereinbefore set forth. 65

3. In combination, the rod f , pulleys $l l$, yokes $k k$, having slotted necks, brackets $e e$, having set-screws $c' c'$, and brake-arms $n n$, connected to bar d' of the moving cores $d d$, substantially as set forth. 70

4. The electro-magnetic device composed of the helices $a a'$, fixed connected cores $c' c'$, and movable connected cores $d d$, in combination with the brake-arms $n n$, pulleys $l l$, yokes $k k$, and carbon rod f , substantially as set forth. 75

In testimony whereof I have hereunto set my hand, at New York, county and State of New York, this 26th day of November, A.D. 1881.

GEO. W. SAWYER.
